This invention relates to light sources for spectroscopic work, and in particular to atomic spectral lamps of the hollow cathode type which are adapted to provide light sources having sharp atomic spectral lines, such as may be made use of in spectroscopy, in particular atomic absorption spectroscopy, optics, metrology, interferometry and the like.

It is presently well-known to produce atomic spectra by means of hollow-cathode tubes. In such tubes the cathode is usually shaped in the form of a hollow cylinder. The configuration of the anode has been thought to be relatively unimportant, being usually either a metallic ring, wire or plate, which is disposed in the vicinity of the cathode and arranged so as not to obscure the direct axial line of vision from the outside of the tube into the interior of the hollow cathode. This arrangement ensures that the luminous discharge within the hollow cathode may be observed without obstruction. The cathode is generally made of the metal whose spectrum it is required to produce. Alternatively a small pellet or the like of the material the spectrum of which is to be produced is located within the cathode, or the material is otherwise incorporated in the cathode. As a further alternative, the cathode may be an alloy containing the metal whose spectrum is required. The anode may be made from any suitable metal, since its material does not affect the spectrum of the discharge within the cathode.

Previously it was thought that, in order to obtain sharp spectral lines suitable for investigations in absorption spectroscopy, the hollow cathode would have to be arranged in a low pressure circulating system, so that gaseous particles, which are emitted from the surfaces of electrodes and enclosures during a discharge may be continuously removed. The presence of such gaseous matter in the discharge space reduces the intensity of the discharge and the sharpness of the spectral lines obtained. This phenomenon is known as "outgassing," and was considered to be a serious obstacle to the successful operation of sealed-off hollow cathode tubes, since the effective life time of such tubes was thought to be considerably limited by the occurrence of outgassing.

It is known that the difficulty referred to above may be overcome to some extent if a gettering material is incorporated in the electrodes of a sealed-off discharge tube, or otherwise located in the tube. The getter, when heated, serves to absorb the residual gases in the tube, and thus minimizes the effect of outgassing. Suitable gettering materials are activated uranium, zirconium and tantalum. The getter is conveniently incorporated in the anode of a sealed-off hollow cathode discharge tube. In such tubes both electrodes are enclosed in a sealed glass or other transparent envelope, which is filled with a rare gas at low pressure, say of the order of 2 mm. of Hg. When a potential of the order of several hundred volts is applied to the electrodes, a luminous discharge is set up between them. By adjusting the pressure of the rare gas in the tube, the luminous region of the discharge is confined to the inside of the cathode. This luminous region constitutes the required light source, having sharply defined spectral lines characteristic of the metals of which the cathode is composed.

2

Discharge tubes of the type described are generally satisfactory in use, but it will be appreciated that, once the glass envelope is sealed, it is impossible to replace or exchange the electrodes of such a tube without destroying the envelope. This means that the spectrum of one element only can be obtained from any one tube. A further disadvantage is that the tubes have generally to be operated from a supply of direct current, thus necessitating the use of a rectifier with the commercially available alternating current supply, since with the usual types of construction the anode would, if it were changed to the cathode by reversal of the potentials, become unduly heated and its spectrum would interfere with that of the other electrode.

It is the main object of this invention to provide a sealed-off hollow cathode discharge tube which is suitable as a source of atomic resonance lines for use in atomic absorption spectrochemical analysis and has improved performance characteristics and lifetime as compared to sealed-off hollow cathode discharge tubes at present in use.

It is another object of this invention to provide a sealed-off hollow cathode discharge tube which is capable of providing the spectra of two or more elements and in which any one electrode can be selected to serve as the cathode.

A further object of this invention is to provide a sealed-off hollow cathode discharge tube which may be operated from a source of alternating current.

30 A sealed-off hollow cathode discharge tube according to the invention comprises a transparent envelope within which are mounted at least two hollow electrodes each of which is adapted to function as a cathode capable of providing an atomic spectral light source, each of the electrodes consisting of, or including, a different element and being arranged so that light from any of the electrodes can be viewed without obstruction by any of the others. To this end, the hollow electrodes are preferably mounted side by side with their axes parallel to each other so that a clear line of vision can be obtained into the interior of each electrode. One electrode may, if desired, be made of or include a gettering material, but as explained hereinafter, the use of gettering material is not normally necessary. The envelope is evacuated and preferably filled with a rare gas at a low pressure.

45 In order that the invention may be more fully understood, two types of sealed-off hollow cathode discharge tubes in accordance with the invention will now be described with reference to the accompanying drawings, in which:

FIGURE 1 is a perspective view of a discharge tube having two hollow electrodes,

FIGURE 2 is an enlarged cross-sectional view of the discharge tube shown in FIGURE 1, and

55 FIGURE 3 is a perspective view of a multi-electrode discharge tube having seven hollow electrodes.

The hollow cathode discharge tube shown in FIGURES 1 and 2 comprises a generally pear-shaped closed glass envelope 4 within which two similar electrodes 5, 6 are 60 mounted by means of lead wires 7, of tungsten or other suitable material such as chrome-iron, which are sealed into the glass wall of the envelope 4 at its narrower end 8. The electrodes 5, 6 are identical in size and shape, being cylindrical with an open end 9 and a closed end 10, which is formed by pinching the respective electrode onto its lead wire 7. In this way mechanical and electrical connections are made between the electrodes and their respective lead wires. The lead wires 7 extend outside the glass envelope 4 and enable electrical potentials to be applied to the electrodes. The open ends 9 of the electrodes 5, 6 are arranged to face in the direction of the

wider end 11 of the envelope 4. This end 11 constitutes a window through which the discharge within either of the electrodes may be observed. The envelope 4 is evacuated and filled with a rare gas at a pressure of the order of 2 mm. of Hg, the evacuation opening 12 being then sealed.

The envelope 4 of the tube is made from C9 glass. The end 11 which comprises the viewing window is made from Corning 9741 glass, which transmits ultra violet radiation, being fused or sealed directly to the body of the envelope 4. The electrodes are each made from a different material. For example, the electrode 5 may be made of iron and the electrode 6 of copper. The best filler gas has been found to be neon, and is therefore generally used for these tubes.

We have observed that the lifetime of the tubes increases rapidly with increasing tube volume. For example, an increase in volume from 75 cm.³ to 250 cm.³ increases the effective tube life from 3A hours to more than 50A hours. It has been empirically determined that the smallest enclosed volume for discharge tubes intended for a reasonably long working life should be of the order of 150 cm.³.

In use of the discharge tube a source of several hundred volts, either A.C. or D.C., is applied to the external terminals of the electrodes. A luminous discharge is set up within the tube and if the pressure of the rare gas filler within the tube is correctly adjusted, the luminous region of this discharge is confined to the inside of the hollow cathode. Since both electrodes are of the same dimensions and have similar environments, either can serve as the cathode by the correct choice of polarity. On alternating current, the two electrodes will alternately serve as the cathode. Accordingly luminous discharges occur alternately within one electrode and then the other, whichever is the cathode at that particular instant. Each luminous discharge exhibits sharp spectral lines characteristic of the material of the electrode within which it occurs. Thus the discharge tube provides two intense light sources having sharp spectral lines of the metals (e.g., iron and copper) of which the two electrodes are made.

It is of course possible to have more than two electrodes of different materials within the glass envelope. One such multiple electrode discharge tube is shown in FIGURE 3. In this case there are seven hollow electrodes 13, which are mounted side by side with their axes parallel inside a glass envelope 14. The electrodes 13 are supported by tungsten lead wires 15, which are brought through the glass envelope and arranged for connection to sources of potential. The wider end 16 of the envelope constitutes a viewing window through which the discharges within the hollow electrodes may be observed.

Pairs of the electrodes may be energised by selectively connecting the electrical supply to their external terminals, and the spectra of any one or more of the elements of which the various electrodes are made may be thus obtained from the one tube.

The preferred method of manufacture of discharge tubes according to this invention will now be described with reference to a two-electrode tube. In this case the glass envelope containing the electrodes is first evacuated, and during this process is internally "torched" vigorously several times by means of a gas flame. The evacuation is conveniently accomplished by an Edwards "Hyvac" mechanical pump, using "Silicone 702" as a pump fluid. After each torching, the evacuation is continued, until a satisfactory vacuum is obtained (pressure of the order of a tenth of a millimetre of mercury). Electrical potential of the order of a few hundred volts is then applied to one of the electrodes, the other being earthed and spectroscopically pure neon is allowed to enter slowly into the envelope. The pressure of the neon is slowly increased until a luminous discharge is obtained, and then the luminous region of the discharge is confined to the interior of the earthed electrode, i.e. the cathode. This pressure, which is measured with a differential manometer,

has been found to be of the order of 2 mm. of mercury. When this stage is reached the discharge is operated for a period at the highest current which is possible without melting the cathode. The discharge is then switched off and the tube is rapidly evacuated while the cathode is still hot. At a certain pressure, which is characteristic of the tube geometry and the cathode material, profuse sputtering occurs, and advantage is taken of this phenomenon to effect a rapid cleaning of the cathode surface.

The process of tube conditioning, including the steps of filling the tube with neon, maintaining the discharge at a high rate for a period ("running" of the tube) and evacuating the tube until sputtering occurs, is repeated several times (six times has been found to be satisfactory) until there is no sign of molecular spectra in the radiation emitted by the discharge. The anode is conditioned similarly by reversing the potentials. The tube is then filled with neon at a pressure at which a uniform glow within the cathode is obtained, and is then sealed off.

It has been found that in pressure controlled closed hollow cathode tubes made by the above method, the life limitation is largely dependent, not on outgassing as hitherto thought, but on "clean-up." The so-called "clean-up" occurs after prolonged operation of a tube, when the molecules of the filler gas are driven by the discharge into the walls of the envelope. This causes the pressure inside the tube to fall whereupon the discharge is at first impaired and later completely quenched. In view of the fact that in these tubes outgassing is not significant, it is possible to dispense with a getter.

From considerations of maximum spectral intensity for a given current, neon was found to be the most favourable of the rare gases for iron hollow-cathodes. Neon is also convenient in that most of its spectrum lines are in the red and do not interfere with the resonance lines of metals, most of which are in the blue and ultra-violet regions of the spectrum. It has, however, the serious disadvantage that it "cleans up" much more rapidly than argon and in terms of long tube-life argon is to be preferred. In general, if a monochromator is used to select a given resonance line, an argon-filled tube is preferable. However, if it is desired to use interference filters, which may have spectral band widths of the order of 100 Å, the argon lines in the blue may prove troublesome—as, for example, when it is desired to isolate the Ca line at 4226 Å. In such cases neon is preferable.

It is possible to provide the spectra of several elements by making one electrode of an alloy of the various metals, or by making a cathode consisting of sections of different metals. The disadvantage of this procedure is that there may be preferential sputtering, and it often happens that this type of tube takes a long time to reach equilibrium conditions. With a brass hollow-cathode, for example, the tendency is for the cathode to become completely covered with a sputtered layer of zinc. In terms of reaching rapid equilibrium the use of cathodes of pure materials is desirable.

Sealed hollow-cathode discharge tubes in accordance with this invention have been made with electrodes of a wide variety of materials, including Ag, Al, Au, Bi, C, Ca, Cd, Cr, Cu, Fe, Hf, Ir, Mg, Mn, Na, Ni, Pb, Pt, Sb, Ti, V, Zn and Zr. Experience indicates that satisfactory sealed-off hollow-cathode tubes could be made for any metal. Some elements, however, require special techniques.

One instance of this occurs when metals of low mechanical strength are used. Examples of these are Pb, Cd, Sb and Bi. Cathodes of these metals easily deform or break as the cathode warms up. The difficulty is overcome by melting some of the metal in the bottom of a hollow-cathode of another material or by using a liner. For low melting-point metals aluminum is a suitable container since it has a simple spectrum.

The preparation of a hollow cathode from an easily oxidisable metal, such as calcium, is perfectly feasible

provided the cathode is kept under oil during the machining process. The washed electrode is then placed in the tube which is evacuated without delay. Some oxide skin is still formed and the tubes take a little more conditioning than those having electrodes of other metals. Sealed-off calcium tubes, however, operate satisfactorily and we have found little difficulty in making such tubes with a lifetime of 50A hr.

In the case of highly reactive metals, such as sodium, hollow-cathodes can be readily made by placing a sodium salt in a cathode of any material, such as aluminum or graphite, having a simple spectrum.

It is to be understood that the tube envelope may be made from materials different from those hereinbefore mentioned. By way of example, W1 glass may be used to form the envelope, while fused silica may be utilized to form the window at the wider end of the tube.

Discharge tubes of the type described herein have been found to be very satisfactory for use in atomic absorption spectrochemical analysis. The general requirement for such work is that the line widths of the resonance lines emitted by the hollow-cathode tube be much smaller than the width of the absorption line of flames. Since the line widths in the flames whose adsorption is to be measured are of the order of 0.03 Å, the general requirement is for hollow-cathodes emitting lines of less than 0.01 Å. half-width. This requirement is easily met by the discharge tubes of the present invention.

We claim:

1. A discharge tube, said atomic spectral light source being confined wholly to the hollow interior of the respective electrode, comprising a sealed envelope, at least two hollow cylindrical electrodes mounted side by side at one end of the envelope with their axes parallel, and a transparent window at the other end of the envelope in axial alignment with the axes of the said electrode, each of the electrodes including a different element and being capable of providing an atomic spectral light source characteristic of that element for providing a spectral line of at least two solid elements, whereby light from any one of the electrodes can be viewed through the window without obstruction by any other of the electrodes.

2. A discharge tube, said atomic spectral light source being confined wholly to the hollow interior of the respective electrode, comprising a sealed envelope, at least two hollow cylindrical electrodes mounted side by side at one end of the envelope with their axes parallel, an atmosphere in the envelope comprising a rare gas at a pressure of the order of 2 mm. of Hg, and a transparent window at the other end of the envelope in axial alignment with the axes of the said electrode, each of the electrodes including a different element and being capable of providing an atomic spectral light source characteristic of that element for providing a spectral line of at least two solid elements, whereby light from any one of the electrodes can be viewed through the window without obstruction by any other of the electrodes.

3. A discharge tube, said atomic spectral light source being confined wholly to the hollow interior of the respective electrode, comprising a sealed envelope, at least two hollow cylindrical electrodes mounted side by side at one end of the envelope with their axes parallel,

lead wires supporting said electrodes and embedded in and extending through said envelope, and a transparent window at the other end of the envelope in axial alignment with the axes of the said electrodes, each of the electrodes including a different element and being capable of providing an atomic spectral light source characteristic of that element for providing a spectral line of at least two solid elements, whereby light from any one of the electrodes can be viewed through the window without obstruction by any other of the electrodes.

4. A discharge tube, said atomic spectral light source being confined wholly to the hollow interior of the respective electrode, comprising a sealed envelope, at least two hollow cylindrical electrodes mounted at one end of the envelope with their axes substantially parallel, an atmosphere in the envelope comprising a rare gas at a pressure of the order of 2 mm. of Hg, lead wires supporting said electrodes and embedded in and extending through said envelope, and a transparent window at the other end of the envelope in axial alignment with the axes of the said electrodes, each of the electrodes including a different element and being capable of providing an atomic spectral light source characteristic of that element for providing a spectral line of at least two solid elements, whereby light from the interior of any one of the electrodes can be viewed through the window without obstruction by any other of the electrodes.

5. A discharge tube, said atomic spectral light source being confined wholly to the hollow interior of the respective electrode, comprising a sealed envelope having an enclosed volume of at least 150 cm.³, at least two hollow cylindrical electrodes mounted at one end of the envelope, an atmosphere in the envelope comprising a rare gas at a pressure of the order of 2 mm. of Hg, lead wires supporting said electrodes and embedded in and extending through said envelope, and a transparent window at the other end of the envelope, each of the electrodes including a different element and being capable of providing an atomic spectral light source characteristic of that element for providing a spectral line of at least two solid elements, whereby light from the interior of any one of the electrodes can be viewed through the window without obstruction by any other of the electrodes.

6. A discharge tube, said atomic spectral light source being confined wholly to the hollow interior of the respective electrode, comprising a sealed envelope having an enclosed volume of at least 150 cm.³, at least two hollow electrodes mounted at one end of the envelope, an atmosphere in the envelope comprising a rare gas, lead wires supporting said electrodes and embedded in and extending through said envelope, each of the electrodes including a different element and being capable of providing an atomic spectral light source characteristic of that element for providing a spectral line of at least two solid elements, whereby light from the interior of any one of the electrodes can be viewed through the window without obstruction by any other of the electrodes.
